UNITED STATES PATENT OFFICE.

HENRY C. DOMEYER, OF SAUVIE'S ISLAND, OREGON.

CHAIN-LOCK IN LOADING OR UNLOADING APPARATUS.

SPECIFICATION forming part of Letters Patent No. 593,928, dated November 16, 1897.

Application filed January 15, 1897. Serial No. 619,381. (No model.)

To all whom it may concern:

Be it known that I, HENRY C. DOMEYER, a citizen of the United States, residing at Sauvie's Island, in the State of Oregon, have invented a new and useful Improvement in Chain-Locks in Loading or Unloading Apparatus, of which the following is a specification, reference being had to the accompanying drawings, forming a part hereof.

The object of my present invention is to improve upon the lock for holding the lower chain or cable ends in a loading or unloading apparatus.

The construction of my improved lock is illustrated in the accompanying drawings, in which—

Figure 1 is an inverted plan with the under plate removed, so as to disclose the arrangement of the locking mechanism. Fig. 2 is a side elevation of one of the bolts constituting a part of the locking mechanism. Fig. 3 is a vertical section on the line $x-x$, intersecting Fig. 1, but including the plate omitted in said Fig. 1. Fig. 4 is an inverted plan of the under plate c , (not shown in Fig. 1,) and Fig. 5 illustrates a coupling device for securing the loose ends of the chains held by my improved lock.

The letters and numbers designate the parts referred to.

The locking mechanism is inclosed within a case constructed of three plates a b c , the first of which is plain and solid and serves as a cover when my lock is set in position to keep obstructions out of the locking mechanism. The plates b c are respectively provided with slots d , e , d' , e' , and f and perforations g h i j k , extending through the plates.

In the slots d e d' e' slide the projecting portions of the bolts l m and in the notches l' m' slide the bridges n n' . The bolts are kept forward by the extending arms of the coil-springs o , held on a post p . The trigger q has two arms q' and q'' , which are inserted in the horizontal slots r , with which the bolts are respectively provided. To the eye s on the trigger is attached a cord t , extending through the eye u , so that the trigger may be operated and the bolts drawn back by pulling on such cord.

v' v^2 v^3 v^4 are four threaded posts extend-

ing through the plates b c and provided with nuts for bolting said plates together.

My lock is designed to hold four chain ends. One of these is held by its end link on the post v^3 , and the end links of the other three chains are attached to anchors 1 2 3, provided with semiannular notches w , by which they are braced against the posts v' v^2 v^4 , the latter serving as fixed abutments for said anchors, and the anchor 3 having a toe 3^a , by which it is held by the bolt l , and the anchors 1 and 2 being constructed and interlocking as shown in Fig. 1, the anchor 1 being held by its toe 1^a by the bolt m , thus drawing back the bolts l m will release the anchors 1 2 3 and the chain ends attached thereto, the lock coming away with the chain attached to the post v^3 . The upper or opposite ends of the chains may be coupled to a device illustrated in Fig. 5, and the chain ends to be coupled may be tightened by means of a lever, also shown and more fully described in another application for Letters Patent filed by me of even date herewith.

Now what I claim is—

1. In a loading and unloading apparatus, the combination of a slotted plate, a bolt slideable therein, fixed abutments on the plate, anchors engaging said abutments loosely or so as to be movable therefrom and held in contact with said abutments by said bolt, chains secured to said anchors, a trigger for moving said bolt, and means for holding the movable parts to the plate substantially as described.

2. In a loading and unloading apparatus, the combination of a slotted plate, a bolt slideable therein, fixed abutments on the plate, anchors engaging said abutments loosely or so as to be movable therefrom and held in contact with said abutments by said bolt, chains secured to said anchors, a spring for retaining said bolt in its operative position, a trigger for moving said bolt, and means for holding the movable parts to the plate substantially as described.

3. In a loading and unloading apparatus, the combination of a slotted plate, bolts slideable in the slots of said plate, fixed abutments on the plate, anchors engaging said abutments and held by said bolts, chains se-

cured to said anchors, a trigger for working said bolts, and means for holding the movable parts to the plate substantially as described.

4. In a loading and unloading apparatus, 5 the combination of a slotted plate, bolts slideable in the slots of said plate, fixed abutments on the plate, anchors engaging said abutments and held by said bolts, chains secured to said anchors, a spring for retaining 10 said bolts in their operative position, a trigger for moving said bolts, and means for holding the movable parts to the plate substantially as described.

5. In a loading and unloading apparatus a chain-lock comprising the slotted and perforated plates *b c* the bolts *l m* the trigger *q* and its operating connections, the spring *o* the posts *v' v² v³ v⁴* the anchors 1 2 3 and the chains, the parts being combined and operating substantially as set forth. 15 20

In witness whereof I have hereunto set my signature in the presence of two witnesses.

HENRY C. DOMEYER.
